COMBINED GOLF CLUB HEAD AND SHAFT SOCKET

John D. Risher, 127 Bonnett St. SW.,
New Canton, Ohio 44720

Filed Nov. 24, 1967, Ser. No. 9,539

Term of patent 14 years

U.S. Cl. D34—5
Int. Cl. D21—03

FIG. 1

FIG. 2

FIG. 3

FIG. 4

FIG. 5

FIG. 6

FIG. 7

FIG. 8

FIG. 9

FIG. 1 is a top plan view of a combined golf club head and shaft receiving socket thereon;

FIG. 2 is a side view in elevation of the club head shown in FIG. 1, and showing the striking face of the club;

FIG. 3 is an end view in elevation of the club head shown in FIGS. 1 and 2, and showing the end adjacent which the shaft socket is disposed;

FIG. 4 is a side view in elevation showing a variant of the concept shown in FIGS. 1-3;

FIG. 5 is a side view in elevation showing a further variant;

FIG. 6 is a side view in elevation showing a still further variant;

FIG. 7 is a rear view of FIG. 4;

FIG. 8 is a rear view of FIG. 5; and

FIG. 9 is a rear view of FIG. 6.

I claim:

The ornamental design for combined golf club head and shaft socket, as shown and described.
